(57) **CLAIM**

The ornamental design for a sealing device for medicine container or medical apparatus, as shown and described.

DESCRIPTION

FIG. 1 is a front perspective view of a sealing device for medicine container or medical apparatus showing our new design;

FIG. 2 is a front perspective view thereof;

FIG. 3 is a front elevational view thereof;

FIG. 4 is a bottom plan view thereof;

FIG. 5 is a cross-sectional view thereof taken along line 5-5 in FIG. 3;

FIG. 6 is a cross-sectional view thereof taken along line 6-6 in FIG. 4;

FIG. 7 is a front perspective view showing the body portion of the device;

FIG. 8 is a perspective view showing the cap portion of the device; and,

FIG. 9 is an enlarged cross-sectional view thereof taken along line 6-6 in FIG. 4.

The broken lines are for the purpose of illustrating environmental structure, and form no part of the claimed design.
